UNITED STATES PATENT OFFICE.

NATHAN M. LOWER, OF PITTSBURGH, PENNSYLVANIA, ASSIGNOR TO LOCOMOTIVE STOKER COMPANY, OF PITTSBURGH, PENNSYLVANIA, A CORPORATION OF PENNSYLVANIA.

LOCOMOTIVE STOKER.

1,410,687.

Specification of Letters Patent. Patented Mar. 28, 1922.

Application filed February 24, 1919. Serial No. 278,917.

To all whom it may concern:

Be it known that I, NATHAN M. LOWER, a citizen of the United States, and resident of Pittsburgh, county of Allegheny, and 5 State of Pennsylvania, have invented certain new and useful Improvements in Locomotive Stokers, of which the following is a specification, and which are illustrated in the accompanying drawings, forming a part 10 thereof.

The invention appertains to stokers in which fuel is discharged into the fire-box through a distributing tube set through the back head, and relates more especially to 15 means for securing the distributor tube in position and for preventing the discharge of flame or smoke from the fire-box around this tube.

In stokers of this type the distributor tube 20 projects into the interior of the fire-box, and being subjected to intense heat is soon burned off, rendering replacement necessary. The tube is placed in position from within the fire-box, the workman being 25 obliged to enter the box for this purpose. As it is frequently necessary to do the work when the engine is too hot to permit a man to remain in the fire-box but a few minutes 30 at a time, it is important that means be provided for securing the tube externally and quickly after it has been put in position. The mechanism for delivering fuel to the distributor tube is massive, and it is further 35 important that the means for connecting and disconnecting the tube be of such a nature that replacement can be made without disturbing the delivery device.

It is further of importance that the distributor tube can be carried by the delivery 40 device and form a part of it rather than of the boiler, in order that the parts may not be strained or broken by expansion and contraction. In service the back head of the boiler is moved backward by expansion to 45 the extent of three-eighths of an inch, or even more. The stoking mechanism is massive and necessarily firmly secured in place, and it must be freed from the expansive movement of the boiler.

50 This feature of the invention consists of a tube having its outer end adapted to fit and be secured to the fuel delivery mechanism, herein shown as an elevator and a feeding elbow, and in sliding relation to

the boiler. An adjustable hook bolt 55 engaging the distributor tube, and being secured between lugs on the elbow by means of a nut, affords the means of attachment, in the illustrated embodiment of the invention. 60

The life of the distributor tube is prolonged by providing for the admission of air around it, the tube being made somewhat smaller than the aperture in the back head of the fire-box through which it projects. 65 It is found in practice that while this expedient is of great value, it has the serious disadvantage that when the engine is not running and there is not a strong stack draft smoke escapes into the cab through the 70 opening around the tube; and if a gas explosion occurs within the fire-box, flames shoot out, endangering the attendant.

A second object of the invention has for its purpose the elimination of these difficulties, and this feature of the invention consists in the combination with a distributor tube loosely fitting through the back head of the fire-box to provide air passages, of a shield surrounding the tube and depending 80 therefrom and being spaced apart from the back head to form an inclosed chamber, this chamber being provided with an opening at or near its bottom for the admission of air.

The third object of the invention is to 85 provide for the fitting of the shield to the back head. The stoker mechanism is usually constructed independently of the locomotive, and installed by its maker. While the manufacturer of the stoker constructs 90 the device in accordance with specifications, and the locomotives which are to be provided with stokers are especially designed for their attachment, it is a common experience to find that the apertures provided 95 in the locomotive for receiving the distributor tubes are not accurately positioned. In order to provide for the application of the stoker to the locomotive, notwithstanding such inaccuracy, it is usual to have the 100 back head aperture made somewhat larger than necessary to receive the tube. That the smoke shield may be secured regardless of the position of the distributor tube within the back head aperture, it is provided with 105 slotted bolt-holes.

In the accompanying drawings—
Fig. 1 is a detail vertical section through

the back head of a fire-box and the distributor tube, the upper end of a fuel elevator being shown in elevation;

Fig. 2 is a detail plan section on the line 5 2-2 of Fig. 1;

Fig. 3 is a detail elevation of the back head of the fire-box and of the outer end of the distributor tube positioned in the shield, the attaching hook bolt being shown in 10 section;

Fig. 4 is a detail horizontal section through the back head of the fire-box, the distributor tube being shown in plan; and

Fig. 5 is a detail rear view of a locomotive 15 with a stoker applied thereto.

The back head of a locomotive fire-box is shown at 10, and as usual is chambered to contain water. This back head is apertured to loosely receive the fuel distributor 20 tube 11, there being a thimble 12 fitted within the aperture to make a water-tight joint.

The tube 11 has its forward end suitably configured to provide for the distribution of the fuel over the entire surface of the grate.

25 The deflecting vanes and top plate render the dimensions of the inner end of the tube greater than that of its body, necessitating the insertion of the tube within the aperture in the back head from within the fire-box.

30 The outer end of the tube is adapted to fit against the end face of the discharge member 13 of the elevator conduit 14. This conduit may bear the same relation to the fire-box as do the elevator conduits shown in Letters Patent No. 1,371,252, issued to me March 15, 1921, and as shown in Fig. 5 of the drawings of this application. Preferably an annular rib 15 is formed upon the face of the discharge member 13, of the conduit, to inclose and make a tight joint with the end of the tube 11.

45 A hook bolt 16, fitting between a pair of upstanding lugs 17 on the end of the outlet member 13 of the conduit 14, enters a suitable aperture in the tube 11. A nut 18, applied to the end of the bolt 16, bears against the rear faces of these lugs and draws the bolt backwardly, and with it the tube 11, securely binding the latter to the member 50 13. The weight of the distributor tube may be, and in the present construction is, relied upon to hold it snugly against the member 13, although the securing means is applied only at the top.

55 A shield plate 19, apertured to slidably receive the outer end of the tube 11, is secured to the back head of the fire-box by suitable bolts, as 20, 20, and 21, 21. This plate is provided with a marginal flange 22, 60 which bears against the outer face of the back head, its body portion being thereby spaced apart from this surface to form therewith an air chamber 23. At the lower portion of the plate there are provided apertures, as 24, 25, for the admission of air. The

air within the chamber 23 is heated by its contact with the surface of the back head, and, rising, flows into the fire-box continuously, even though the forced draft may be discontinued,—the difference in pressure between the outside air and the vapors within the fire-box also causing such inflow. When the development of smoke is excessive, with low draft, outflow of smoke around the tube is prevented by a colder air column within 75 the shield chamber below the tube. Should there be a gas explosion within the fire-box sufficient to force a flame outward around the distributor tube, it will be deflected downwardly through the chamber 23 and discharged along the surface of the back head, between it and the conduit 14, without endangering the occupants of the cab.

The distributor tube 11 is supported entirely by the member 13, though in the adjustment of the device it may contact with the shield plate 19. The slideable relation of this plate with the tube permits of the expansion of the boiler without placing strain upon the fuel elevating and discharging mechanism.

80 The bolts 20, 21, set through elongated apertures in the plate 19, the upper apertures accommodating the bolts 20 being preferably shown inclined and the lower apertures accommodating the bolts 21 being vertically elongated. These apertures being sufficiently wide to form a loose fit for the bolts, permit of the proper positioning of the plate, notwithstanding any irregularities 95 which may have occurred in locating the aperture in the back head. An impelling steam jet is indicated at 26.

I claim as my invention—

1. In a locomotive stoker, in combination, 105 fuel delivering means comprising a discharging member provided with a pair of outstanding lugs, a distributor tube adapted to extend from the member through the back head of a locomotive fire-box and having an aperture adjacent its outer end, a bolt having a hook for engaging in the aperture, the body of the bolt extending between the lugs, and a nut applied to the end of the bolt and bearing against the lugs.

110 2. In combination, a fire-box having an aperture in its back head, a fuel distributor tube projecting loosely through the aperture to provide an air passage along its outer surface, and a shield plate apertured to snugly fit upon the outer end of the tube and having marginal flanges bearing against the outer surface of the back head and having an aperture below the tube.

115 3. In combination, a fire-box having an aperture in its back head, a fuel distributor tube projecting loosely through the aperture to provide an air passage along its outer surface, a shield plate apertured to snugly fit upon the outer end of the tube and having 120

marginal flanges bearing against the outer surface of the back head and having an aperture below the tube, and having elongated holes for receiving attaching bolts for engaging the back head.

4. In combination, a fire-box having an aperture in its back head, a fuel distributor tube projecting loosely through the aperture to provide an air passage along its outer

10 surface, a shield plate apertured to slid-
ingly fit upon the outer end of the tube and
having marginal flanges bearing against the
outer surface of the back head and having
an aperture below the tube and having elong-
ated holes for receiving attaching bolts for
engaging the back head.

5. In a locomotive stoker, in combination,
a fuel conduit having a discharge member,
and a tube for delivering fuel to the loco-
motive fire-box, such tube being secured to

the member by means engaging its top wall
and being held to the face of the member
by its own weight.

6. In a locomotive stoker, in combination,
a fuel conduit having a discharge member,
and a tube for delivering fuel into the fire-
box of the locomotive, such tube being se-
cured to the member by a hook engaging its
upper wall and being held to the end face
of the member by its own weight. 30

7. In a locomotive stoker, in combination,
a fuel conduit having a discharge member,
a pair of spaced lugs projecting from said
member, a tube for delivering fuel into the
fire box of a locomotive, a hook engaging 35
said tube and having a nut resting upon said
lugs, said tube being held to the face of said
member by its own weight and being remov-
ably suspended by the hook.

NATHAN M. LOWER.
